[57] **CLAIM**

The ornamental design for a tool for applying caulking material, as shown and described.

DESCRIPTION

FIG. 1 is a diagrammatic perspective view of the tool for applying caulking material.

FIG. 2 is a right side elevational view thereof, the left side elevational view being a mirror image of the right side view.

FIG. 3 is a top plan view thereof.

FIG. 4 is a bottom plan view thereof.

FIG. 5 is a front elevational view of the tool for applying caulking material; and,

FIG. 6 is a rear elevational view thereof.
